UNITED STATES PATENT OFFICE.

HARRY G. GEISSINGER, OF NEW YORK, N. Y., ASSIGNOR TO VAPOR CAR HEATING COMPANY, INC., OF CHICAGO, ILLINOIS, A CORPORATION OF NEW YORK.

AUTOMATICALLY-CONTROLLED CAR-HEATING SYSTEM.

Application filed September 9, 1918. Serial No. 253,323.

To all whom it may concern:

Be it known that I, HARRY G. GEISSINGER, a citizen of the United States, residing at New York, in the county of New York and 5 State of New York, have invented certain new and useful Improvements in Automatically-Controlled Car-Heating Systems, of which the following is a specification.

My invention relates to apparatus for controlling the operation of heating systems, 10 more particularly steam heating systems, on railway cars.

One of the objects of the invention is to provide a simple, inexpensive and practical 15 control mechanism for a railway car heating system by means of which the car may be maintained automatically at one of several selected temperatures. For example, the invention provides an arrangement whereby 20 the atmosphere in the car may be maintained at a normal living temperature of seventy degrees Fahrenheit, or thereabouts, while the car is being occupied during the day time; at a lower temperature, for instance sixty 25 degrees Fahrenheit during the night hours when the car is occupied; and at a still lower temperature, for instance, at fifty degrees Fahrenheit, when the car is standing idle in the yards. The invention has in view both 30 the comfort of the traveling public and the saving of steam. It is usual to heat passenger cars while they are standing in the yards and it is highly desirable that regulation of the heat at such times be automatic as the 35 yard men cannot be relied upon to watch over the operation of the heating apparatus. Ordinarily cars have been heated up to normal while in the yards. This is wholly unnecessary and involves a large waste of fuel.

40 In the drawings—

Fig. 1 is a diagram illustrating the entire control system as applied to a railway car heating apparatus of the vapor type having a primary and an auxiliary radiator,

45 Fig. 2 is a fragmentary view, partly in section and partly in elevation, showing more in detail but also to some extent diagrammatically, certain of the devices employed for controlling the passing of steam 50 through the radiators, and

Fig. 3 is a sectional view of a vapor regulator employed to prevent the introduction of steam to the radiator, in larger quantities, than can be condensed.

Like characters of reference designate like 55 parts in the three figures of the drawings.

Referring first to Fig. 1 of the drawings, A designates the steam train pipe of a railway car, and B and C two radiating coils located in the car, which may be termed primary and auxiliary radiators, respectively. D is a vapor regulator of common construction designed to prevent the passing of steam through the radiators, which at their discharge ends are open to the atmosphere, in 60 greater amounts than can be condensed in said radiators. The type of vapor regulator preferably used in the heating system illustrated consists of a casing provided with a high pressure chamber D² communicating 65 through pipe D⁹ with the train pipe A, a low pressure chamber D³ communicating through pipe D¹⁰ with the four-way valve E, and a discharge chamber D⁴ open to the atmosphere. The high and low pressure chambers 70 are in communication with each other through a port which is closed by an automatically operated valve D⁵. This valve is opened and closed by means of a thermostat D⁸, a rod D⁷ supported thereon, and a bell crank D⁶ to which the valve and rod are connected. The thermostat consists of a cell 75 filled with a fluid which expands when steam comes into contact with the cell. E is a four-way valve for controlling the circulation of 80 the heating medium through the primary radiator B, and F a similar valve for controlling the circulation through the auxiliary radiator C. These valves preferably stand 85 open under normal conditions and are closed 90 by the operation of air motors G and H. Air for actuating these motors is taken from the air train line J, forming part of the air 95 brake system of the car, and its application to the motors is controlled by a magnetically actuated air valve K. L is what may be termed a radiation valve adapted, in one 100 position, to effect the closing of the auxiliary radiator valve F of the auxiliary radiator, and in the other position to subject this valve 105 to the control of the air valve K which latter, in the preferred embodiment of my invention, at all times controls the valve E of the primary radiator.

The air valve K is governed in its movement automatically by a thermostatic mechanism, preferably by three thermostats M, N and O which may be made effective, se-

lectively, to control the heating system by operation of the switch P. The thermostat M, which will be termed the high temperature thermostat, is set to break its circuit at a relatively high temperature, for instance, seventy degrees Fahrenheit, and operates, when selected to control the heating system, to maintain the temperature of the car at seventy degrees Fahrenheit. The 10 thermostat N, which may be termed the medium temperature thermostat, is intended to control the heating system during the night while the car is occupied and set to operate at sixty degrees Fahrenheit, or at 15 such other temperature as may be desired. The thermostat O, which is termed the low temperature thermostat, is set to operate at a considerably lower temperature, for instance, at fifty degrees, and is intended to 20 control the heating system when the car is standing unoccupied in the yard. During such periods it is only necessary to keep the car at such temperature as will prevent 25 freezing of water pipes and fixtures, injury to the finish of the car, and the like; and, inasmuch as the ordinary passenger car is out 30 of service on an average for considerably more of the time than it is in service, a very important saving in fuel results from this reduction of temperature in the car while in the yard.

Referring now to Fig. 2, the casing of the four-way valve E is divided into four chambers 25, 26, 27 and 28. These chambers are 35 put into communication with each other in pairs by the revoluble valve member 29 which is shown as provided with an operating lever 30. The lever 30 is connected with the piston 31 of the air motor G by a 40 connecting rod 32. 33 is a spring which exerts tension on a lever 34 engaged with the connecting rod 32. In the normal position of the parts of the apparatus the valve member 29 stands in its open position under the 45 action of spring 33. The valve is closed by movement of piston 31 when the motor is under air pressure. The inlet pipe 35 of the primary radiator B leads from chamber 26 of the four-way valve E. The return pipe 36 of the primary radiator discharges into chamber 27.

In an actual installation I prefer to employ an air motor constructed as shown in my co-pending application Serial No. 55 253,322 filed September 9, 1918. As the construction of the motor is covered by the application just referred to, and as the particular construction of the motor is not important, so far as the invention disclosed 60 in the present application is concerned, it has been thought sufficient to illustrate the motor in this application in as simplified a form as possible.

The four-way valve F for the auxiliary 65 radiator C and the air motor H for operat-

ing this valve are preferably the same in construction as the corresponding devices used in connection with the primary radiator and in the drawings the parts are given corresponding reference numerals distinguished by the exponent letter "a." 70

Chamber 25^a of four-way valve F is connected by a pipe 37 with chamber 28 of the four-way valve E. The inlet pipe 38 of the auxiliary radiator leads from chamber 26^a 75 of valve F and the return pipe 39 of the auxiliary radiator discharges into chamber 27^a. 40 is a pipe which leads from chamber 28^a of valve F to the thermostatic member of the vapor regulator. 80

The magnetic air valve K, as shown in the drawings herein, is fundamentally the same as the air valve disclosed in my co-pending application above referred to but is simplified herein for the purpose of clearness of illustration. It comprises a casing 41 which is formed to provide a cylinder 42 of relatively small diameter and a larger cylinder 43. In these cylinders operates a double piston valve member 44 having a piston 45 to fit cylinder 43 and a piston 46 to fit cylinder 42. The casing 41 is also provided with a magnet chamber 47 in which is located an electro-magnet 48 having a pivoted armature 49 connected with a valve 50 which, when the magnet is deenergized, is adapted to close an exhaust port 51 leading from the chamber 47, and, when the magnet is energized, to close a port 52 extending from chamber 47 to cylinder 42 under piston 46. 100 Cylinder 42 is open to the atmosphere through a port 53 in the upper end of the cylinder and cylinder 43 is connected by a pipe 54 with the magnet chamber 47. 55 is a pipe leading from the air line J to a 105 pipe 56, 56^a, one section 56 of which extends to a port 57 in the air valve casing 41, this port communicating with port 52 above described, the other section 56^a extending to the three-way cock L which has been termed the radiation valve. 58 is a pipe leading from cylinder 42 to the air motor G, and 59, 59^a a branch pipe from pipe 58 to the air motor H, this branch pipe having interposed therein the radiation valve L. The 110 latter has a revoluble valve member 60 provided with a through port 61 and a branch port 62 at right angles thereto which extends half way through said member. 115

The thermostats M, N and O are preferably of the type indicated, that is, they are composed, in each case, of a chord member 63, which is the member of major expansibility, and an arc member 64. The thermostats are circuit breaking thermostats adapted to break their respective circuits on rise of temperature to a given point. Below these points the thermostats close their circuits. 120

The operation of the apparatus above de- 130

scribed is as follows: In the drawings the parts of the apparatus are shown in the position which they assume when the car is subject to control by the medium temperature 5 thermostat N and is at a temperature below that at which this thermostat operates to break its circuit and cause the inflow of medium to the radiators or the active radiator to cease. The car temperature, it 10 will be assumed, is above that for which the low temperature thermostat O is set so that the arc member 64 of this thermostat is out of contact with the opposed contact member 65. Thermostats N and M are both 15 in contact with their contact members 66 and 67 so that both circuits are closed so far as the thermostats are concerned. However, the high temperature circuit is open at the selective switch P. This switch is on contact 20 68 of the circuit through the medium temperature thermostat N. This circuit is as follows: from battery 69 by wire 70 to selective switch P, contact 68, wire 71, contact 66, thermostat N, wire 72, wire 73, wire 25 74, resistance 75 and wire 76 to the battery. The magnet 48 is on a shunt from the circuit above described (and the other thermostat circuits to be described hereinafter), being connected by a wire 77 with switch P 30 and by a wire 78 with wire 74. The circuit through the magnet 48 is of greater resistance than the thermostat circuit so that so long as the thermostat circuit remains unbroken magnet 48 will not receive sufficient 35 current to operate the valve 50. The compressed air from the air brake system will, therefore, pass through port 52 into the magnet chamber 47 and through pipe 54 to cylinder 43. Pressure exerted on the piston 40 45 of the double valve 44 will overbalance that exerted against the piston 46 of the valve. Therefore no air will pass to the air motor G nor, assuming that the radiation valve L is in the position shown in Fig. 2, 45 will any air pressure be exerted upon the air motor H. The radiator valves E and F will stand open and steam in the train pipe, reduced to substantially atmospheric pressure by the vapor regulator D, will pass 50 first through the primary radiator B and then through the auxiliary radiator C. The water of condensation outflows through pipe 40. Excess of steam in the radiator or radiators will result in the discharge of the 55 excess to the thermostat of the vapor regulator which is thereby actuated to throttle inflow as in the ordinary vapor system.

As soon as the temperature in the car reaches that for which thermostat N is set, 60 the circuit previously traced through this thermostat is broken at a point between the thermostat and contact 66 and magnet 48 is energized, which causes valve 50 to be raised, opening port 51 and closing port 52, 65 thereby relieving the pressure from the mag-

net chamber 47 and cylinder 43. The double piston valve 44 is raised and air under pressure flows from pipe 55 through pipe 56, port 57, and cylinder 42 and pipe 58 to the valve motor G which is actuated to close 70 the valve against the tension of spring 33. The compressed air also similarly actuates the valve motor H of the auxiliary radiator provided the radiation valve is in the position shown in Fig. 2.

By moving the selective switch P the heating apparatus may be put under control either of the low temperature thermostat O or the high temperature thermostat M. The selective switch, in each case, closes a circuit through the thermostat selected for controlling the operation of the system. The circuit through the low temperature thermostat O will be as follows: battery 69, wire 70, selective switch P, contact 79, wire 80, contact 65, thermostat O, wire 81, wires 73, 74, resistance 75 and wire 76 to the battery.

In case the high temperature thermostat is selected the circuit will be as follows: battery 69, wire 70, selective switch P, contact 82, wire 83, contact 67, thermostat M, wire 84, wires 73 and 74, resistance 75, and wire 76 to the battery.

The description of the operation of the apparatus as given above assumes that the radiating element of the heating system is active as a whole, that is to say, in the particular embodiment shown, that both radiating coils are active and function as a single 100 unit. If it is desired to decrease the capacity of the system, which decrease will have the advantage of shortening the course through which the steam and water of condensation must flow, this can be done by 105 shifting the handle 85 of the radiation valve L from the position shown in full lines in Fig. 2 to that indicated by the dotted lines. In this position of the radiation valve air pressure is applied directly to the air motor 110 H of the auxiliary radiator through pipe section 56^a and ports 61 and 62 of the revoluble member 60 of the radiation valve. This shifts the valve member 29^a of the four-way valve F ninety degrees, short circuiting the auxiliary radiator so that the medium from the primary radiator passes from chamber 28 of four-way valve E through pipe 37 and chambers 25^a and 28^a of valve F directly to the discharge pipe 40 115 which leads back to the vapor regulator D. Valve F is now freed from control of the thermostatic mechanism (consisting of the thermostats M, N and O, and the magnetic air valve K and associated parts) and it will 120 so remain until the radiation valve is moved to its original position. As soon as this is done the valve of the auxiliary radiator is again placed under the automatic control of the thermostatic mechanism which governs 130

the valve of the primary radiator. In other words, the apparatus is capable of manual manipulation to cut out a part of the radiation surface but whenever this part 5 of the radiation surface is active it is necessarily under control of the thermostats which govern the circulation of medium through the rest of the system. It is not possible to manipulate the radiation valve 10 so that the auxiliary radiator can be cut in and not be subjected to control by the thermostatic mechanism which (subject to the ultimate control of the vapor regulator) determines the amount of heating medium delivered to the radiation surfaces.

It will be apparent that the multiple temperature regulation, which is a preferred feature of my invention, might be employed in connection with a single radiator; and, 20 on the other hand, that the multiple coil system with arrangements for cutting one coil in or out of the system might be employed in connection with a thermostatic device actuated at one temperature only.

25 The controlling system herein shown and described is susceptible of other modifications without departure from the principles of my invention. Therefore, I wish it to be understood that the invention is not to be considered as limited to the particular 30 embodiment thereof shown and described, the scope of the invention being expressed in the claims appended hereto.

I do not claim herein, either by itself, 35 or in combination with the multiple number of car thermostats, the arrangement of two radiating coils capable of separate and conjoint control, as shown and described, for the reason that this arrangement is the subject matter of a copending application filed by me on May 1, 1922 Serial No. 557,534 as a division hereof.

I claim:

1. A car heating system comprising, in 45 combination, a radiator, a source of supply of heating medium, a valve to govern the introduction of medium to the radiator, a thermostatic mechanism for controlling said valve comprising a plurality of circuit 50 breaking thermostats arranged in independent circuits, and a switch which is adapted to close said circuits selectively to maintain the atmosphere of the car at a high temperature, a low temperature, or a temperature intermediate said high and low temperatures.

2. In combination with a railway car 60 provided with a source of supply of air under pressure, a radiator in the car, a mechanism for controlling the introduction of heating medium therein comprising a radiator valve, a pressure actuated motor for operating the valve, and a plurality of thermostats for controlling said motor each of 65 which is set to control the system at prede-

termined temperatures, so that the car may be maintained at a high temperature, a low temperature, or a temperature intermediate said high and low temperatures.

3. In combination with a railway car provided with a source of supply of air under pressure, a radiator in the car, a mechanism for controlling the introduction of heating medium therein comprising a radiator valve, a pressure actuated motor for 70 operating the valve, an electrically actuated device for controlling the air pressure to the motor, a plurality of thermostats arranged in independent circuits and set to operate at different car temperatures, and a 75 switch for closing said circuits selectively, whereby a high temperature, a low temperature, or a temperature intermediate said high and low temperatures may be maintained in the car, as desired. 80

4. In combination with a railway car provided with a source of supply of air under pressure, a radiator in the car, a radiator valve which normally stands open, an air pressure motor for closing said valve, and a plurality of thermostats set to operate at 90 different car temperatures which may be made effective, selectively, for controlling the application of air pressure to said motor, whereby a high temperature, a low 95 temperature, or a temperature intermediate said high and low temperatures may be maintained in the car, as desired. 95

5. In combination with a railway car provided with a source of supply of air under 100 pressure, a radiator in the car, a radiator valve which normally stands open, an air pressure motor for closing said valve, an electrically actuated device which controls the application of air pressure to said motor, a plurality of thermostats set to operate 105 at different car temperatures for controlling said electrically actuated device, and a switch by means of which said thermostats may be made effective, selectively, 110 for controlling said heating system, whereby a high temperature, a low temperature, or a temperature intermediate said high and low temperatures may be maintained in the car, as desired. 115

6. In combination with a railway car provided with a source of supply of air under pressure, a radiator in the car, a radiator valve which normally stands open, an air pressure motor for closing said valve, three 120 thermostats arranged in independent circuits which they are adapted to break on rise of the car temperature to respectively different points, a switch for closing said circuits selectively, and an electrically actuated device for causing the application of air to the motor, which device is arranged in a shunt from said thermostat circuits of greater resistance than said circuits. 125

HARRY G. GEISSINGER,
